FACSIMILE TRANSCEIVER APPARATUS OR SIMILAR ARTICLE

James S. MacConkey, 5706 Bashaw, Westerville, Ohio
43081, and David D. Tompkins, 5809 Satinwood Drive,
Columbus, Ohio 43224

Filed Aug. 6, 1973, Ser. No. 386,101

Term of patent 14 years

Int. Cl. D14—03, 01
U.S. Cl. D26—14 R

Fig. 1

Fig. 2

Fig. 3

*Fig. 4**Fig. 5*

FIG. 1 is a right-hand front perspective view of a facsimile transceiver apparatus or similar article;

FIG. 2 is a top plan view thereof;

FIG. 3 is a left-hand elevational view thereof, the right-hand end elevation being a mirror image thereof;

FIG. 4 is a front elevational view thereof; and

FIG. 5 is a rear elevational view thereof.

We claim:

The ornamental design for a facsimile transceiver apparatus or similar article, as shown and described.
